CLAIM

The ornamental design for a levitation base, as shown and described.

DESCRIPTION

FIG. 1 is a perspective view of the levitation base showing our new design;

FIG. 2 is a front view thereof;

FIG. 3 is a rear view thereof;

FIG. 4 is a left view thereof;

FIG. 5 is a right view thereof;

FIG. 6 is a top view thereof;

FIG. 7 is a bottom view thereof; and,

FIG. 8 is another rear view of the levitation base in a use state.

The broken lines in the figures show portions of the levitation base that form no part of the claimed design. The additional broken lines shown in FIG. 8 show environmental structure that form no part of the claimed design.

1 Claim, 5 Drawing Sheets
